UNITED STATES PATENT OFFICE.

JAMES T. CARADINE AND WILLIAM T. CHRISTMAS, OF ST. LOUIS, MISSOURI.

DESIGN FOR A HAT.

Application filed December 19, 1925. Serial No. 15,798. Term of patent 14 years.

To all whom it may concern:

Be it known that we, JAMES T. CARADINE and WILLIAM T. CHRISTMAS, citizens of the United States, residing at St. Louis, State of Missouri, have invented a new, original; and ornamental Design for Hats, of which the following is a specification, reference being had to the accompanying drawing, forming part thereof.

The figure is a view in elevation of the

hat, showing our new design which is formed by the grouping at the front, back and sides of the crown of metal eyelets of contrasting color.

We claim:

The ornamental design for a hat, substantially as shown and described.

J. T. CARADINE.
WM. T. CHRISTMAS.
